LOUIS F. SYLVESTER, OF HOBOKEN, NEW JERSEY, ASSIGNOR TO NATIONAL FIRE PROOFING COMPANY, OF PITTSBURGH, PENNSYLVANIA, A CORPORATION OF PENNSYLVANIA.

CENTERING FOR CONCRETE ARCHES.

1,108,639.

Specification of Letters Patent. Patented Aug. 25, 1914.

Application filed November 1, 1911. Serial No. 657,947.

To all whom it may concern:

Be it known that I, LOUIS F. SYLVESTER, a citizen of the United States, residing in Hoboken, county of Hudson, and State of New Jersey, have invented a certain new and useful Centering for Concrete Arches, of which the following is a specification.

This invention is a centering for arches, more particularly concrete arches, and the object of the invention is a structure adapted to be used in the construction of arches of various spans and depths.

With this object in view, the centering consists of two members adjustable to and from each other, whereby they may be positioned at the ends of arches of various spans, the space intermediate the two members being closed by sheathing boards. Each of the said members is composed of a haunch board and extension pieces which form the support for the sheathing. Preferably a portion of the sheathing is fixedly attached to the extension pieces at the ends where said pieces join the haunch board, the said extension pieces, haunch board and the attached sheathing forming an adjustable unit.

The soffit board is attached to soffit blocks, and these parts are suspended below a metal girder, as is customary, but the novel addition to this structure is the provision of means for retaining the adjustable members in position upon said soffit blocks. In order that the centering may be used on arches of varying depths, I make provision for inserting padding between the soffit board and the soffit blocks.

Heretofore in the construction of concrete arches it is customary to make the centering in one of two ways. One way was to nail the various parts of the form together, said parts being of such size and arrangement as to fit the form of arch which it was proposed to make. According to this method it will be noted that a new construction was required for each size of arch. This procedure necessitated assembling and dismantling of the form in such way that there resulted a great waste of lumber. The other expedient used in the construction of arches was to make up a permanent form by nailing the various parts together, and after the construction of the arch removing the form without dismantling its parts. The disad-

vantage of this latter method is that such a form can be used only in the construction of an arch corresponding to the dimensions of the permanent form. For the reasons given, such methods are expensive and troublesome. The present invention obviates the various difficulties referred to, and embodies a simple and economical way of using the adjustable parts referred to in the construction of arches varying in span and depth.

Other features of the invention, and the advantages thereof, will appear from the following detailed description when taken in connection with the drawings.

In the accompanying drawings, I have illustrated one practical embodiment of the invention, but the construction shown therein is to be understood as illustrative, only, and not as defining the limits of the invention.

Figure 1 is a vertical cross section illustrating the new centering in co-operative relation to adjacent beams for the purpose of molding a concrete arch in the space between the beams and for enveloping said beams with concrete material. Fig. 2 is a plan view of the structure illustrated in Fig. 1. Fig. 3 is a detail perspective view illustrating one of the unitary members or sections of the improved centering. Fig. 4 is a detail perspective view illustrating a soffit board and soffit blocks which are adapted to be suspended below each beam for the purpose of supporting the members or sections of the centering. Fig. 5 is a vertical cross section through one beam, a soffit board co-operating therewith, and soffit blocks for said board, said view illustrating a method of "padding" the soffit board in order to support it at different distances below the bottom flange of the beam. Fig. 6 is a detail view illustrating a filler strip which may be used in connection with the soffit blocks and a haunch board of one unitary member or section of the centering, for the purpose of supporting the haunch board in an elevated position relative to the soffit blocks. Fig. 7 is a view showing an additional supporting means for the soffit board. Figs. 8 and 9 are details of the invention.

In the example shown in Fig. 1, the concrete material is to be molded in the space between adjacent parallel I-beams A, B, the

75

85

90

100

105

top surface of the concrete material X being substantially flush with the top flanges of said beams. Under such conditions the centering is suspended from the beams in a position to support the concrete material across the span between the beams until said concrete material shall have become set, and the centering operates, also, to mold the concrete material around the webs and flanges of the beams. Below the bottom flanges of the adjacent beams are positioned soffit boards 10, 11, said boards extending lengthwise of the beams, and being arranged a suitable distance below the bottom flanges of said beams, so as to leave spaces intervening between the soffit boards and the bottom beam flanges. Each soffit board is attached to a plurality of soffit blocks, the soffit blocks of the board 10 being designated at 12, whereas the soffit blocks of the board 11 are indicated at 13. Each soffit board is of a desired length and width, and a suitable number of soffit blocks are used in connection with each board. If a short board is employed, two or three soffit blocks may be fastened thereto, but it is preferred to employ comparatively long soffit boards, and to attach a series of soffit blocks to the long board. In some cases I use a soffit board which is sixteen feet in length, and fasten four soffit blocks to the board, at suitable intervals. The soffit blocks are of such length as to exceed the width of the soffit board, and these blocks and the board are attached, either directly or indirectly. The soffit blocks are positioned transversely beneath the soffit board, the end portions of each soffit block extending beyond the respective side edges of the soffit board. Ordinarily, the board and the series of blocks are attached directly together by nails or other fasteners indicated at 14, but in some cases it is necessary to employ "padding" 15 between the board and the blocks, as shown in Fig. 5, whereby the soffit board is supported in a raised position with respect to the series of transverse soffit blocks. The padding 15 consists of one or more strips positioned between the board and the blocks, and as shown, the padding is fastened by nails 16 to the soffit blocks, and the board is fastened by nails 17 to the padding strips, but if desired, nails 17 may pass through the board and padding and into the soffit blocks, thus dispensing with nails 16, although it is preferable to fasten the padding to the soffit blocks, and the board to the padding, in the manner shown in Fig. 5. Each soffit block is provided in its top edge with notches 18, 19, said notches being spaced with relation to each other, and the two notches being positioned beyond the respective side edges of the soffit board. In lieu of the notches, I may employ other means, such as stop blocks 20 shown in Fig. 6, said

blocks 20 being fastened to the top edges of the soffit blocks so as to occupy a spaced relation to the respective side edges of the board. Suitable means are provided for suspending the soffit boards and the soffit blocks below the respective beams A, B. As shown, a series of metallic hangers 21, 22 are employed, said hangers being looped around the soffit blocks and looped, also, around the top flanges of the girder. Each hanger is composed of metal, preferably strong flexible wire, which is looped around the soffit block, on one side of the soffit board, said wire extending upwardly along side of the beam, and having its top end bent over the beam and caught below the top flange thereof. Two wire hangers are shown as engaging with each soffit block, the wire hanger 21 being positioned at one side of the soffit board and being bent at its upper end in one direction over the top flange of the beam, whereas the other hanger 22 is looped around the soffit block at the opposite side edge of the soffit board, and its upper end is bent to extend in an opposite direction across the top of the beam. It will be understood that the two wire hangers are used in connection with each soffit block of the series attached to the soffit board, and thus two series of hangers are used at intervals 95 throughout the length of the soffit board. If desired, however, the soffit board may be supported intermediate the soffit blocks and the adjacent hangers 21, 22 by the wires 23. The wires 23 are looped around the soffit board intermediate the soffit blocks, and they are bent so as to catch into the bottom flange of the girder, see Fig. 7, whereby each soffit board is supported by a series of hangers attached to the soffit blocks thereof and said soffit board is braced intermediate the soffit blocks by the wires or hangers 23, the latter being attached to the bottom flange of the beam.

The described construction provides a secure means for supporting the soffit blocks and the soffit board below the beam, so that the soffit board will occupy a stationary horizontal position below, and parallel to, the bottom flange of the beam, whereby the soffit boards are adapted to support a thickness of concrete material below, and in contact with, the bottom flanges of the respective beams.

The concrete material in the span between the adjacent girders is supported by unitary members, indicated in their entirety by the reference characters C, D, and by one or more loose sheathing boards E, said unitary members or sections being adjustable with respect to each other so as to adapt the two members for use in connection with spans of varying widths. The spaces between members C, D, when they are extended to their full width, are closed by the employment 130

of a number of sheathing boards E, which rest loosely upon certain arms of the respective members.

The detailed construction of the adjustable members C, D is as follows: Member C embodies a haunch board 24, a plurality of horizontal arms 25, and one or more sheathing boards 26. The haunch board 24 may consist of one, two or more pieces to 10 which are attached vertical cleats 27. The arms 25 are fastened in any suitable way to the cleats or to the haunch board, or to both the cleats and the haunch board, and the angle joint between the arms and the 15 haunch board is strengthened by metallic angle irons or straps 28, the latter being shown as nailed to the cleats 27 and to the extension arms 25. Arms 25 are substantially at a right angle to the haunch 20 board, and they are spaced with reference to each other, said arms being parallel. The sheathing boards 26 which enter into the construction of section or member C are fastened permanently to the extension arms 25 25 of said member or section, a suitable number of these sheathing boards 26 being employed, three being shown. The other member or section D of the centering is similar in construction to the member C, that is to 30 say, member D consists of a haunch board 29 composed of one or more pieces, extension arms 30 attached to the haunch board and extending at a right angle thereto, a proper number of sheathing boards 31 fastened to the extension arms, cleats 32 secured to one face of haunch board 29 and to extension arms 30, and a metal brace or strap 33 secured to the cleats and the extension arms. The arms 25 of section C 35 and the arms 30 of section D extend for suitable distances beyond the permanently attached sheathing boards 26, 21, respectively. When the sections C, D are assembled between two adjacent beams, the span between 40 which is less than the aggregate length of the centering formed by members C, D, the extension arms 25, 30 of the respective sections C, D will overlap each other at the middle portion of the span. For supporting 45 the adjacent ends of the sections C, D, stretchers G and one or more runners H, are employed. Each stretcher G consists of a strip or length of material, preferably wood, of the required dimensions, said stretcher 50 being long enough to extend between the adjacent end of two soffit blocks 12, 13 on the adjacent soffit boards 10, 11. Each stretcher rests at its end portions upon the two soffit blocks, and it is retained in position upon 55 said soffit blocks by suitable means which allows the stretcher to be easily removed when the centering is to be taken down. If desired, the respective end portions of the stretcher may be temporarily nailed to the 60 adjacent soffit blocks, but it is preferred to

employ clips g for retaining each end portion of the stretcher in a fixed relation to one soffit block. The clip g is composed of a metal plate which is bent into a loop so as to embrace the bottom and two side edges 70 of the stretcher. Said clip is provided, preferably, with another clip g', the latter embracing the soffit block adjacent to the notch 19 therein. Clip g is fastened in position by clip g' embracing the soffit block and 75 being fastened thereto in a suitable way, whereby the clip g' operates to strengthen the soffit block adjacent to the notch 19 therein, thus preventing the soffit block from breaking when the haunch board is engaged 80 with the notch. A series of stretchers G are employed across the span between the beams, the end portions of each stretcher being supported by two adjacent soffit blocks. The runner H is positioned upon the series of 85 stretchers G. Said runner H extends lengthwise of the arch, and is positioned substantially midway between the beams. This runner is of suitable length, thickness and depth to support the extension arms 25, 30 90 of sections C, D, respectively, said extension arms of the sections resting upon the runner, whereby the inner ends of sections C, D are upheld by the series of stretchers and the runner. Obviously, two or more runners 95 may be positioned upon the stretchers for supporting the extension arms of the respective sections C, D, and if desired, the runners may be elevated with respect to the stretcher by the use of "padding" h, see 100 Fig. 9, said padding consisting of blocks or strips attached to the stretcher and adapted for engagement with the runner.

Assuming that it is desired to use the centering between adjacent beams separated by 105 a span of a definite width, I proceed as follows to install the centering. The soffit boards 10, 11 are placed in position below the lower flanges of the beams, and the hangers 21, 22 are looped around the soffit 110 blocks which are attached to said boards, the upper ends of the hangers being bent around the top flanges of the beams. The stretchers are now placed in position between the beams, so that the end portions of 115 the stretchers rest upon the soffit blocks, the clips g engaging with said end portions of the stretchers to retain the latter in position. One or more runners H are now placed upon the stretchers, substantially midway between, and parallel to, the beams. The unitary sections C, D are now positioned between the beams. The haunch board 24 of section C fits into the notches 19 of the soffit blocks 12 so that the haunch board is 120 adjacent to beam A and soffit board 10, the arms 25 of said member or section C extending to and across the runner H. The haunch board 29 of section D fits into the notches 18 of soffit blocks 13, said haunch 125 board 130

board 29 being adjacent to beam B while arms 30 of section D extend to and across the runner H. The arms 25, 30 of sections C, D, respectively, thus rest upon the runner in a manner for the arms to substantially overlap each other, whereby the inner end portions of sections C, D, are supported by the runner and the stretchers. The permanent sheathing boards 26, 31 of sections 10 C, D, may be sufficient to practically cover the span between the beams, particularly if said span is a narrow one, but in case the permanent sheathing boards do not fully cover the span, then additional sheathing 15 boards E are placed upon the extension arms 25, 30 of the respective sections. The centering is now positioned to receive the concrete material, which material may be dumped or otherwise deposited upon the 20 sheathing boards, and against the haunch boards of sections C, D, and upon the soffit boards 10, 11. The concrete material is thus supported below and around the beams by the soffit boards and the haunch boards, and 25 said material is supported between the beams by the sheathing boards which are attached to, or rest loosely upon, the sections C, D. The concrete material is thus filled in and around the beams and upon the 30 centering so that the slab of concrete material is substantially flush with the top flanges of the beams as indicated at X, in Fig. 1. If desired, the extension arms 25, 30 of the 35 respective sections may be provided with perforations through which are adapted to be driven nails, as at h', see Fig. 1, for the purpose of fastening the arms of the sections in position relative to the runner.

The centering operates to support the concrete material and to hold it until said material becomes set and hardened. When it is desired to remove the centering the runner H is withdrawn, stretchers G lifted out of position upon the soffit blocks, and the wires 45 of hangers 21, 22 are cut, whereupon the soffit blocks and soffit boards are lowered away from the concrete material around the beams, and the unitary sections C, D, may thus be withdrawn from the span of concrete material. It is evident that the several parts composing the centering may be 50 easily and quickly disconnected and removed.

In molding the concrete around beams of 55 a certain height it becomes necessary at times to raise the soffit boards with respect to the soffit blocks, and this is accomplished in my invention by the employment of padding 15 which is interposed between the blocks and the board. Again, it is necessary 60 at times to elevate the haunch boards 24, 29 relative to the soffit blocks, and to retain said haunch boards in operative positions relative to said blocks. This result is secured by the employment of filler blocks I

which are inserted into the notches 18, 19 of the soffit blocks, see Fig. 6. The haunch boards are adapted to rest upon the filler blocks I, and they are engaged by blocks 20 which are fastened to the soffit blocks, whereby the haunch boards are adapted to fit in notches between the soffit boards and the blocks 20.

In molding the concrete material between wide arches the soffit blocks and soffit boards are installed as heretofore described, stretchers G and runners H are placed in position, and sections C, D are positioned between the beams, said sections being moved away from each other or drawn apart in order that the haunch boards may rest upon the soffit blocks. The extension arms 25, 30 of the two sections permit this relative adjustment between said sections in order to accommodate the centering to arches having spans of different widths. When the sections are drawn apart the arms thereof rest upon one or more runners, and said arms operate to support the loose sheathing boards which are employed to fill in the space between the permanent sheathing boards attached to the sections.

From the foregoing description, it is apparent that the centering of my invention may be used in installing arches, the spans of which vary in width and the concrete of which is to be molded around beams of varying heights. The centering may thus be adapted for supporting concrete material which is to be molded into an arch either flush with the beams, or raised slightly above the beams, or depressed slightly below the beams, as may be deemed necessary.

While I have described the centering as adapted for use in molding plastic material around and between the beams, it is evident that the invention may be used for other purposes.

From the foregoing description it is evident that certain parts of the centering are adapted for use repeatedly in molding arches the depth and width of which may be of various dimensions. It is not necessary to nail lumber together in order to produce the forms required for molding the concrete on every job of work, for the reason that the soffit boards and soffit blocks, the unitary members or sections, the stretchers, the runners, and the sheathing boards may be assembled in a manner which requires very little nailing, whereby the material of the centering remains intact and does not become filled with nail holes, nor does it split or crack, which objections are inherent in the common method of producing forms for each particular job. Accordingly, I am enabled to effect material economy in the lumber required in the operation of installing forms suitable for molding concrete arches.

My new centering fulfills all the conditions

in molding concrete for arches the width of which varies, and wherein beams of different depths and of different widths of flanges, are used. In arches, of different dimensions, 5 beams are used which vary in depth and in the width of the flanges. The two sections C, D, extensible or collapsible with respect to each other, and the parts associated therewith, make provision for the use of the centering in arches the width of which varies. 10 The means for "padding" the soffit board relative to the soffit blocks, for suspending the soffit blocks, and for supporting the haunch boards upon the soffit blocks, provide 15 for molding the concrete to the desired depth around beams the vertical dimensions of which vary in the different arches. The notches 18, 19, in the soffit blocks are of such length as to exceed the thickness of the 20 haunch boards (see Fig. 5), and thus the haunch boards are adjustable in the notches of the soffit blocks so that the haunch boards will be movable relative to the width of the beam flanges, whereby the haunch boards are 25 adapted to be placed in operative relation to beams the flanges of which vary in width. It is evident that soffit boards of different widths are to be used in connection with beams the bottom flanges of which vary in 30 width, and this use of different widths of soffit boards is rendered possible by positioning the haunch boards in the notches of the soffit blocks in such manner that the haunch boards are shiftable relative to the beam flanges. 35 When the soffit board and the haunch boards are properly assembled relative to the beam and the soffit blocks, any space in the notches 18, 19 left unfilled by the haunch boards may be filled in by filler 40 blocks so as to secure a tight engagement of the haunch boards with the notched soffit blocks.

Having thus fully described the invention, what I claim as new, and desire to secure 45 by Letters Patent is:

1. A centering for constructing arches between parallel beams embodying a series of hangers attached to said beams and depending therefrom, soffit boards positioned 50 below said beams, substantially parallel thereto, said soffit boards being supported by said hangers in spaced relation to the under surfaces of said beams, unitary sections positioned to span the space between 55 said parallel beams, each section comprising a haunch board and a plurality of arms attached to the haunch board and extending horizontally therefrom so that the section is adapted as a unit to be placed in 60 position and to be removed when required, said haunch boards of the two unitary sections being supported adjacent to the sides of the suspended soffit boards so as to be in spaced relation to the adjacent beams and 65 said horizontal arms of one unitary section

being in overlapping relation to the similar arms of the other unitary section, means by which the horizontal arms of the two sections are upheld between the haunch boards, and sheathing boards supported on said horizontal arms between the haunch boards. 70

2. A centering for use in installing arches embodying soffit boards adapted to be positioned below the beams, soffit blocks fast with said soffit boards, the length of each soffit block exceeding the width of the soffit board to which it is attached, means for suspending the soffit blocks from the beams, and unitary sections or members positioned between the soffit boards, each section or member having a haunch board which is supported by the extended end portions of the soffit blocks of one soffit board. 75

3. A centering for use in installing arches embodying soffit boards adapted to be positioned below the beams, soffit blocks fast with said soffit boards, the length of each soffit block exceeding the width of the soffit board to which it is attached, means for suspending the soffit blocks from the beams, unitary sections or members positioned between the soffit boards, each section or member having a haunch board which is supported by the extended end portions of the soffit blocks of one soffit board, and means 80 for retaining the haunch board in position 85 with relation to the soffit blocks. 90

4. A centering for use in installing arches embodying soffit boards provided with attached soffit blocks, said soffit blocks being 100 extended at their ends beyond the side edges of the soffit boards and said extended end portions of the soffit blocks being provided with notches, suspending means engaging with the soffit blocks for supporting the soffit boards in position below certain beams, and unitary members or sections positioned 105 between the beams, each member or section being provided with a haunch board which is engaged with the notches of the soffit blocks on one soffit board. 110

5. A centering for use in installing arches embodying soffit boards provided with attached soffit blocks, the ends of which are extended beyond the side edges of the soffit 115 boards, means for supporting the soffit boards in operative positions relative to certain beams, stretchers extending between the beams, said stretchers being supported by the extended end portions of the soffit blocks, unitary members or sections each provided with a haunch board positioned to be supported by the extended end portions of the soffit blocks, and means on the stretchers for supporting the adjacent ends of the unitary sections or members. 120

6. A centering for use in installing arches embodying soffit boards provided with attached soffit blocks, the end portions of which are extended beyond the side edges 130

- of the soffit boards, means for supporting the soffit boards in operative positions relative to certain beams, stretchers extending between the beams, said stretchers being supported by the extended end portions of the soffit blocks, means for retaining the stretchers in fixed relation to the soffit blocks, unitary members or sections each provided at one end with a haunch board which is positioned to rest upon the extended end portions of the soffit blocks of a soffit board, and means carried by the stretchers for supporting the adjacent ends of the members or sections.
- 15 7. A centering for use in installing arches embodying soffit boards provided with attached soffit blocks, the end portions of which are extended beyond the side edges of the soffit boards, metal-hangers attached to the extended end portions of the soffit blocks and engaging with certain beams for supporting the soffit boards in operative positions below the beams, stretchers extending between adjacent beams, said stretchers being carried by the extended end portions of the soffit blocks, unitary members or sections each provided with permanent sheathing boards and with a haunch board which is positioned to rest upon the extended end portions of the soffit blocks on a soffit board, means carried by the stretchers for supporting the adjacent ends of said members or sections, and additional sheathing boards resting upon the members or sections intermediate the permanent sheathing board thereof.
8. A centering for use in installing arches embodying a series of soffit blocks positioned beneath, and crosswise of, certain beams, means for suspending the soffit blocks from the beams, soffit boards positioned above and attached to the soffit blocks, the end portions of which soffit blocks are extended beyond the side edges of the soffit boards, means intermediate the soffit blocks and the soffit boards for raising the latter relative to the former, stretchers supported by the extended end portions of the soffit blocks, unitary members or sections supported by the soffit blocks and the stretchers, and a sheathing board or boards resting on the members or sections.
- 10 9. A centering for use in installing arches embodying a plurality of soffit boards each provided with transverse soffit blocks, said soffit blocks being extended at their ends beyond the side edges of the soffit boards and said extended ends of the soffit blocks being provided with notches, means for supporting the soffit boards in operative positions with relation to certain beams, stretchers carried by the soffit blocks, unitary members or sections each having a haunch board positioned to engage with the notches of the soffit blocks, means carried by the stretchers for supporting the adjacent ends of the sections or members, a filling for the notches in the soffit blocks whereby the haunch boards may be raised, and means for retaining the haunch boards in position upon the introduction of the notch fillings.
- 15 10. A centering for use in installing arches embodying a plurality of soffit boards each provided with transverse soffit blocks, said soffit blocks being extended at their ends beyond the side edges of the soffit boards and said extended ends of the soffit blocks being provided with notches, means for supporting the soffit boards in operative positions with relation to certain beams, clips attached to the extended end portions of the soffit blocks, stretchers resting upon the soffit blocks and retained in position by the clips, unitary members or sections each having a haunch board positioned to rest upon the soffit blocks, and within the notches thereof, and means carried by the stretchers for supporting the adjacent ends of the members or sections.
- 20 11. In testimony whereof I have signed my name to this specification in the presence of two subscribing witnesses.
